UNITED STATES PATENT OFFICE.

CYRUS E. FRYE, OF INDIANAPOLIS, INDIANA, ASSIGNOR OF ONE-HALF TO
HERMAN L. KUTTER, OF HAMILTON, OHIO.

BOARD-MACHINE.

SPECIFICATION forming part of Letters Patent No. 727,538, dated May 5, 1903.

Application filed January 12, 1903. Serial No. 138,621. (No model.)

To all whom it may concern:

Be it known that I, CYRUS E. FRYE, a citizen of the United States, residing at Indianapolis, Marion county, Indiana, have invented 5 certain new and useful Improvements in Board-Machines, of which the following is a specification.

This invention pertaining to board-machines will be readily understood from the following description, taken in connection with the accompanying drawings, in which—

Figure 1 is a side elevation of a portion of my improved machine; Fig. 2, a side elevation of the remaining portion thereof, the two 15 figures of drawings to be viewed as conjoining with Fig. 2 at the right of Fig. 1; and Fig. 3, a diagrammatic vertical longitudinal section of the entire machine upon a reduced scale.

20 In the manufacture of board on cylinder-machines it is found that the press-rolls remove the marks of the cylinder-mold or of a wire very much more perfectly than they do the marks produced by a felt, the consequence being that most paper-board is much smoother upon one side than the other. When 25 a considerable multiplicity of making-cylinders are employed in the production of very thick board, the arrangement is very often or 30 generally such as to produce felt-marks upon both sides of the board, thus resulting in a product having neither side smooth. Where machines with a considerable number of making-cylinders have been arranged to avoid 35 this and bring the plies together in such manner as to have either one or both of the surfaces free from felt-marks, the arrangement has been extremely complicated, troublesome, and expensive in construction, use, and 40 maintenance. By means of my invention I am enabled to employ an unlimited number of making-cylinders and to avoid the production of more than one felt-mark surface upon the board, and this by means of a very simple 45 organization comparatively inexpensive in use and maintenance.

I illustrate my invention in connection with a machine provided with five making-cylinders.

50 In the drawings, 1 indicates the first cylinder-vat; 2, the making-cylinder therein; 3,

the couch-roll of the cylinder, all these parts being constructed and arranged as usual in cylinder-machines; 4, 5, 6, and 7, successive similar making-cylinders with their vats and couch-rolls; 8, a suction-box arranged in advance of the final cylinder 7; 9, 10, and 11, a series of primary pairs of press-rolls arranged in advance of the suction-box; 12, the first press; 13, a felt-stretcher considered as a whole 55 disposed prior to the first cylinder; 14, a felt whose lower leaf passes successively over each cylinder between them and their couch-rolls, then over the suction-box, then between all of the primary press-rolls, then over the upper 60 roll of the press, then to the upper leaf of the felt, back over the couch-rolls, and to the felt-stretcher, and thence through the course described; 15, extra supporting-rolls for the upper leaf of the felt; 16, wringing-rolls engaging 65 the felt before it reaches the first cylinder; 17, felt-beater coöperating with the usual spray-pipes to wash the felt before it goes to the wringing-rolls; 18, the felt-guide roll; 19, a head-roll for the wire, the same being disposed below the lower leaf of the felt between 70 the final cylinder and the suction-box; 20, a wire which, starting at head-roll 19, passes forwardly under the lower leaf of the felt and over the suction-box and with the felt between 75 the primary press-rolls, thence around the lower roll of the first press, and thence back to roll 19; 21, a stretch-roll for the wire; 22, a guide-roll for the wire, and 23 a felt beyond 80 the first press for picking up the board 85 delivered by the first press and conveying it to further presses and the driers.

Cylinder 2 delivers its product up against the lower leaf of the felt, which carries it forward to a point where the product of the second cylinder 4 is delivered up against the first, and so on till the felt has passed the final cylinder 7, carrying with it the combined product of the five cylinders. Upon reaching roll 19 the product is received between the 90 lower leaf of the felt and the upper leaf of the wire and is carried over the suction-box, which extracts much of the water. The product is thus carried between the felt and the wire to and between the first press 12 and 95 then delivered to the aprons 23. With such a thick product as five cylinders are in-

tended to make it is not found practicable to subject the web at once to the action of the first press 12, owing to the liability of crushing. Therefore before the web goes to the first press it is subjected to the excessive pressings of the primary press-rolls, each of which may successively exert a heavier pressure than its predecessor, thus fitting the web for the final squeeze of the first press. As regards each pair of primary press-rolls it should be noted that the two rolls of the pair should have their axes in a common plane perpendicular to that of the wire and felt passing between them.

It is to be noted that the product delivered by the first press has but one side subjected to felt-marking, notwithstanding five making-cylinders are employed, and that a single felt only is necessary. The wire employed is a comparatively short one, and its original expense and maintainance is less than that of the felts usually employed in the comparatively complex organizations found necessary in bringing about one smooth side for thick board produced from as many as five or more making-cylinders. It will furthermore be observed that all of the cylinders are arranged in simple manner upon a common level and that there is an absence of the overhead work usually involved in machines having the capacity of this one.

If a bottom felt were employed instead of the bottom wire 20 of my system, the felt would absorb water squeezed out of the sheet and might at the last pair of primary press-rolls impart part of its moisture to the sheet. The wire-cloth of my arrangement will not thus retain the water, and therefore a less number of primary press-rolls may be used and a heavier sheet made without fear of crushing. Again, a thicker sheet to the given weight may be made with this arrangement, because the sheet does not require so much pressing and calendering to remove felt-

marks, this matter being very important with board-makers, since they are anxious to get as thick a sheet with given weight as possible.

I claim as my invention—

1. In a board-machine, the combination, substantially as set forth, of a horizontal series of cylinder-machines, a suction-box in advance thereof, primary press-rolls in advance of the suction-box, a first press beyond the primary press-rolls, a felt engaging the upper roll of the first press and having its lower leaf lying between the primary press-rolls and over the suction-box and between the cylinder and couch-roll of all the cylinder-machines and having its upper leaf passing above said couch-rolls, a head-roll disposed below the felt between the suction-box and the final cylinder-machine, and an endless wire engaging said head-roll and the lower roll of the first press and having its upper leaf passing along with the felt between the primary press-rolls and over the suction-box.

2. In a board-machine, the combination, substantially as set forth, of a horizontal series of cylinder-machines, primary press-rolls in advance of the cylinder-machines, a first press beyond the primary press-rolls, a felt engaging the upper roll of the first press and having its lower leaf lying between the primary press-rolls and between the cylinder and couch-roll of all the cylinder-machines and having its upper leaf passing above said couch-rolls, a head-roll disposed below the felt between the first primary press-rolls and the final cylinder-machine, and an endless wire engaging said head-roll and the lower roll of the first press and having its upper leaf passing along with the felt between the primary press-rolls.

CYRUS E. FRYE.
